UNITED STATES PATENT OFFICE.

SAMUEL D. GOSWICK, OF MINERAL WELLS, TEXAS.

ROBBER EXTERMINATOR.

Application filed August 14, 1923. Serial No. 657,463.

To all whom it may concern:

Be it known that I, SAMUEL D. GOSWICK, a citizen of the United States, residing at Mineral Wells, in the county of Palo Pinto and State of Texas, have invented certain new and useful Improvements in Robber Exterminators, of which the following is a specification.

This invention relates to devices which are designed to protect banks and mail trains or the like against robbery, and wherein means is provided for electrocuting the robbers, so that the invention is herein termed a robber exterminator.

The primary object of the invention is to provide a device of the above kind which will be extremely efficient in operation, that can be cheaply and easily installed upon existing mail trains or cars or in banks, and which will not be objectionable in appearance when installed.

Other objects will appear as the nature of the invention is better understood, and the same consists in the novel form, combination and arrangement of parts hereinafter more fully described, shown in the accompanying drawings and claimed.

In the drawings, wherein like reference characters indicate corresponding parts throughout the several views,

Figure 1 is a somewhat diagrammatic plan view illustrating the invention applied to a bank,

Figure 2 is an enlarged vertical sectional view showing details of the invention and taken upon line 2—2 of Figure 1,

Figure 3 is a cross sectional view of the form of conductor blocks employed in the device shown in Figure 1,

Figure 4 is a view partly in side elevation and partly in vertical section showing the invention applied to a mail car, and,

Figure 5 is a fragmentary sectional view showing details of the hand rail construction employed in the device shown in Figure 4.

Referring more in detail to the drawings, and particularly to Figures 1, 2 and 3, 5 indicates a conventional form of bank building having a main entrance as at 6 adjacent to which, at one side of the building, is pro-

vided the usual booth or enclosures 7 and 8 wherein business is generally transacted by the higher officers of the bank. The bank also includes a central series of compartments 9 for the different tellers of the bank which booths are placed between the enclosures 7 and 8 and a safe or vault 10.

The enclosures 7 and 8 are generally formed by relatively low partitions or fences 11 which are provided with swinging gates or doors 12 through which the persons may pass for entering either of these closures 7 or 8 or for passing from one to the other and for passing from the enclosure 8 to the hallway or portion of the office 13 which is located near the teller both 9 and which leads to the entrance of the vault 10. In accordance with the present invention, the doors or gates 12 as well as the door 14 for the entrance to the vault 10 are made of suitable metal which will act as conductors for electricity, the door 14 being attached to metallic rails 15 provided around the interior of the vault 10.

Arranged at some suitable point within the vault 10 is a step up electrical transformer 16 the secondary wires of which are respectively attached to the rail 15 and electrical conducting mats 17 disposed upon the floor of the vault. These mats 17 are electrically connected as at 18 with a further mat 19 that is placed upon the floor of the bank outside of the vault 10 and about the latter as clearly shown in Figure 1. The mat 19 is in turn electrically connected as at 20 with a further mat 21 that is disposed in front of the enclosures or compartments 7 and 8, and these mats are preferably constructed as shown in Figure 3 of wire mesh having their edges bound as at 22.

The railing 15 is in electrical connection with the door 14 and with a screen cage 23 that is placed about the vault 10, and an electrical connection is provided as at 24 between the cage 23 and conducting rails 25 that are disposed on top of the upper edges of the fences 11. The rails 25 are preferably of channel form as shown in Figure 2 so as to fit upon the fences 11 and have a neat appearance, and the doors or gates 12 are electrically connected to these rails 25 by suit-

able connections through the hinges of said gates.

Current is supplied from any suitable source through a wire 26 to one side of the 5 primary of the transformer 12, and a wire 27 extends from the other side of said primary to a main or master switch 28 that is preferably located in the front enclosure 7. The other side of the line is provided by 10 means of the wire 29 which connects the other side of the switch 28, and it will thus be apparent that when the switch 28 is closed, the high tension current will be supplied to the doors or gates, the mats, rails 15 and screens so that when a person bridges certain of these elements the current will flow through his body and electrocute him. For instance, a person standing upon the mat 21 and touching the gate 12 of either 20 compartment or touching the rail 25 thereof will complete the circuit by the passage of the current through his body. In a like manner, the person standing upon the mat 19 or 17 and touching the door 14, cage 23 25 or railing 15, will be subjected to the high tension current for a similar result.

In order that the primary circuit may be completed by any one of the tellers, the line wires 27 and 29 are provided with 30 sub-switches 30 that are arranged in parallel across the primary circuit as clearly shown in Figure 1, one switch 30 being provided in each of the booths 9 so as to be capable of use irrespective of the position 35 of the switch 28.

Referring to the form of the invention shown in Figures 4 and 5, the body of a mail car is usually provided with front doors 5' and 6' and side doors 7', and a 40 threshhold or platform 8' is provided outside of each of the doors 5' and 6' through which one may gain access to the car and ordinary metallic steps indicated at 9' permit access through the doors 7'.

45 In accordance with the present invention a metallic conducting plate 10' is placed upon or embedded in the upper surface of each of the platforms 8' at the threshhold of each door, and all of these plates as 50 well as the steps 9' are electrically connected to one side 11' of the secondary of a step-up electrically transformer 12'. For assisting the persons in mounting the steps 9', hand rails are usually provided in a 55 vertical position at each side of the door openings at the sides of the car, and in the present instance these rails are indicated at 13' and constructed of suitable conducting metal, the ends of which are engaged 60 by binding posts or bolts 14' which pass through the sides of the car for securing the rails rigidly in place. The binding posts 14' besides forming attaching means for the hand rails 13' also provide means 65 for electrically connecting wires 15' there-

to, which wires branch from a main wire 16' that connects with the door knobs 17' of the front and rear doors 5' and 6'. For obvious reasons, the wires 16' are connected to the outer members of the door knobs 17' and the latter are of conducting material while the inner members of said knobs 17' are of insulating material as clearly shown in Figure 4. The lower end of one of the hand rails 13 is electrically connected 75 as at 18 with the other side of the secondary of the transformer 12, and the latter may be suitably mounted in a casing 19 fixed beneath the floor of the car as shown.

One side of the primary of the transformer 12 is connected with a suitable source of electricity by means of a wire 20, and this source of electricity may consist of a storage battery 21 also mounted within the casing 19 and having its other terminal connected by a wire 22 and a main wire 23 with one side of each of the switches 24 that are arranged within the car adjacent the doors 5 and 6. The other side of each of the switches 24 is connected with the other side of the primary of the transformer 12 by means of a branch wire 25. It will thus be seen that when either or both of the switches 24 are closed by an attendant within the car, the current it allowed to flow through the primary circuit and cause a high tension current in the secondary circuit to pass to the plate 10, hand rails 13 and door knobs 17. The current will also flow to the steps 9 through 100 the wires 26. Thus, if one should attempt to rob the train, by forcing an entrance thereto, he will be immediately electrocuted by the high tension current when standing upon the steps 9 or plates 10 and at the 105 same time grasping any of the hand rails 13 or knobs 17.

It will thus be seen that the invention broadly involves floor mats or plates and closure members such as doors or gates, 110 respectively electrically connected to opposite sides of the secondary of a step-up transformer, and relatively arranged so that the same will be naturally bridged by the person attempting to open the closure or gate, means being provided under manual control of the primary circuit of the transformer for rendering the secondary circuit live or dead at will.

115 In this manner, the attendants are not subjected to danger of handling the high tension wires, and the switches may therefore be of any well known or conventional type which are utilized for control of low voltage currents.

120 Minor changes may be made without departing from the spirit and scope of the invention as claimed.

What I claim as new is:—

125 In combination with an enclosure having 130

a hand rail and provided with a metallic threshold plate, said hand rail being a conductor of electricity, a transformer having its secondary respectively connected at opposite sides with the hand rail and threshold plate, a primary circuit including the primary of said transformer, and manually

controlled switches within the enclosure for closing the primary circuit of the transformer at any desired one of a plurality of points within the enclosure.

In testimony whereof I affix my signature.

SAMUEL D. GOSWICK.
